[57] CLAIM

The ornamental design for an ocular housing for a rifle scope, as shown and described.

DESCRIPTION

FIG. 1 is a perspective view of an ocular housing for a riflescope, showing my new design, the broken line showing of a portion of the riflescope is for illustrative purposes only and forms no part of the claimed design; FIG. 2 is a side elevational view thereof; and FIG. 3 is an elevational view thereof, taken along line 3—3 of FIG. 2.
